FLEXIBLE DENTURE

Ed C. Sherrod, Bishop, Calif.

Application January 17, 1955, Serial No. 482,090

4 Claims. (Cl. 32—2)

The present invention relates generally to dental prosthesis and specifically to an improvement in the assembly and construction of dentures.

The primary object of the present invention is the provision of a new and improved denture having a relatively flexible anchor-frame of spring steel so that the denture may exert a constant pressure on the alveolar process of approximately forty (40) millimeters, and one which provides such a pressure over the entire denture seating area of the process.

Another object of the present invention is the provision of a flexible denture which assumes a compensating shape for any change of the denture seating area due to resorption or illness, and thereby maintaining a close apposition and contact of the denture base to the tissue of the mouth.

Another object of the present invention is the provision of a flexible support for the artificial teeth in the denture, and which affords elasticity to the denture while it distributes the stress or bite pressure over all of the teeth of the denture.

Another object of the present invention is the provision of a flexible support for the artificial teeth which permits the selection of a base material for resiliency and adhesion, and not ability to stand stress, as has been necessary prior to this invention.

Another object of the present invention is the provision of a spring steel wire imbedded in the base material at or near the peripheral extensions of the denture base, and which permits less bulk of material in the denture base and which maintains a permanent peripheral seal.

Another object of the present invention is the provision of an entirely resilient denture, which by virtue of the constant pressure of spring tension and the close adaptation of the base material and gingival mucous membrane, will maintain and contribute to the normal tissue tone of the gingiva and permit the natural stimulating movements of the tissue in mastication.

Another object of the present invention is the provision of a flexible and resilient denture base which permits any necessary expansion and distortion for insertion and which resumes its normal shape and designed-pressure against the entire denture seating area after insertion. This feature permits the same adaptation and adhesion to the undercut and indented portions of the denture seating area as to the lingual, buccal and labial crests and ridges of the process.

A further object of the present invention is the provision of an improved method of arrangement and setting of individual artificial teeth, and which more satisfactorily fulfills the necessary requirements of balanced occlusion and articulation. The apertures through the teeth along their anterior-posterior axes are located in relation to the occlusal surfaces of the teeth; buccolingually and labiolingually the positioning of the aperture insures the proper proximal relationship of each tooth to the adjacent teeth in the same arch.

2

A further object of this invention is the shaping of the tooth wire to the proper landmarks of the maxillary and mandibular casts, so that the teeth when arranged and strung on wire 10 in proper sequence will satisfy the necessary requirements of denture balance, individual tooth position, ridge relation, arch form (anterior and posterior) overbite, overjet, cuspid position and relation, compensating curves, and contacts in centric, right lateral, left lateral and protrusive.

10 These and other objects and advantages of the invention will be fully apparent upon consideration of the following description when taken in connection with the annexed drawings, in which like reference characters indicate like parts throughout the several views, and in which:

Fig. 1 is a top plan view of the metal skeletal framework of the invention.

Fig. 2 is a front view in elevation of the framework seen in Fig. 1.

20 Fig. 3 is a side view in elevation of the framework shown mounted on the alveolar process.

Fig. 4 is a perspective view of a maxillary or upper denture constructed of the materials of the present invention and showing the framework in dotted lines.

25 Fig. 5 is a schematic top plan view of a mandibular or lower denture showing in dotted lines the flexible movement laterally.

Fig. 6 and Fig. 6a are cross sectional views taken on line 6—6 of Fig. 5 showing the flexing laterally of the mandibular denture in this illustration.

Fig. 7 and Fig. 7a are side elevational views showing the vertical flexing of the mandibular denture of Figs. 6, 6a.

30 Fig. 8 is a vertical cross sectional view showing the flexing of the base material when constructed with the materials and by the methods of the present invention.

Referring more particularly to the drawing, in Fig. 1, is seen the metal framework of this invention, and consisting of a centrally disposed tooth wire 10 of roughly 40 a U-shape, on which are strung the teeth 11 as shown most clearly in Fig. 4 and Fig. 8, each tooth being cast with an aperture 12 of close tolerance dimensions relative to the wire 10, the holes or apertures 12 being through the minor axis of each tooth.

45 The degree of tolerance between any tooth and the tooth wire 10 may be none or any desired amount for any individual tooth or groups of teeth in a denture. Through the posterior molars the degree of tolerance may be little or none, and anteriorly, progressively more toward the central incisors.

50 It is preferable that any degree of tolerance shall be along the major axis of the tooth. Thus the rigidity of the denture may be controlled in its various parts and the bite pressure transmitted to any desired area may be relieved or intensified without interference with the adaptation of the denture seating area.

Further seen in Fig. 1 is the lingual wire 13, conforming to the lingual surface of the alveolar ridge and approximately outlining the peripheral extension of the base material 14, in which the wire 13 is imbedded, as seen most clearly in Figs. 5 and 8. The ends of the wire 13 conform to and return over the alveolar ridge near the posterior border of the retromolar pad on the mandible, and at the pterygomaxillary notch on the maxilla, where they meet and are attached to the tooth wire 10, as seen most clearly at 15, Figs. 1 and 5.

55 In Figs. 1 and 4 are seen the buccal-labial wires 17, which are formed to fit the outer sides of the alveolar process, and as seen in the dotted lines of Fig. 8 that this wire, embedded in the lingual and buccal base material 14, is flexible outwardly and inwardly to press with constant pressure on the sides of the alveolar process, or that

portion of the gum and bone structure that is undercut as at 19.

In Figs. 5, 6 and 6a, the lateral flexing of the invention is indicated by the dotted lines indicating their normal and flexed arch line.

In Fig. 7 and Fig. 7a the denture of this invention is seen to flex vertically also, the suspension of each tooth on the wire 10, and the embodiment of a resilient base material permitting a slight but appreciable flexing.

In constructing this invention, it is preferable to use 10 spring steel wire for all of the wires 10, 13, 16 and 17, while any plastic, rubber, synthetic rubber, or rubber like material may be used for the base material 14.

It is preferable also, the shaping of all the wires and the calculating of the lateral spring tension shall be performed on a cast, or positive mold, made from an impression of the anatomical object on which the restoration is based. The completed assembly of teeth on wire may then be incorporated in a temporary base plate, adapted to the same cast, and waxed up and carved to anatomical contour. Foiling, flasking and packing with the base material may be done in the usual manner and with commonly used equipment, or by any method desired. Due care must be taken to properly space all wire frame work and joints in the base material when packing the flask or mold.

Relative to the construction of complete maxillary and mandibular dentures, the tooth wire 10 is formed to the desired arch from registrations and landmarks on the cast. The teeth with properly placed apertures 12, Figs. 6 and 6a, through the anterior-posterior axis are arranged in proper sequence on the tooth wire 10 as shown in Figs. 4 and 5. The lingual wire 13 as seen in Fig. 1 is shaped to the cast with proper allowance for permissible lateral pressure of approximately forty (40) millimeters, and adaptation mesially-distally to the alveolar process, and the ends turned distally over the ridge to intersect and attach to the ends of wire 10 by a rigid joint, as seen at 15, Figs. 1 and 5.

The buccal-labial wire 17 is shaped and contoured to contact the buccal-labial surface of the alveolar process with a lateral pressure of approximately forty (40) millimeters and return mesially over the ridge to intersect and affix to wires 10 and 13 in a rigid joint, as best seen at 15, Fig. 1.

In the maxillary, this joint is placed as near center of the pterygo-maxillary notch as physiological practice will permit. In the mandibular, this joint is located posteriorly to the retromolar triangle. The joint which unites wires 10, 13 and 17, and/or any other wire or wires employed to contribute and maintain the desired lateral pressure may be made by soldering, brazing, fusion weld, or by any method desired.

The location and amount of steel framework within each denture may vary with the individual application and may be eliminated entirely except for the tooth wire 13 in any type of base material which is flexible and can be used in this invention for the purposes stated.

While only a single embodiment of the present invention has been shown and described, it is contemplated

that the invention may encompass many forms and embodiments without departing from the spirit and scope of the invention as defined in the appended claims.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. A flexible denture comprising a resilient, flexible spring steel wire formed into a substantial dental arch, said wire being shaped to the dental arch, artificial teeth having aligned apertures through their anterior-posterior minor axes, said wire extending through said aligned apertures in said artificial teeth, and a flexible base material covering all exposed portions of said wire and the base of said artificial teeth, and forming the denture saddle.

2. A flexible denture comprising a resilient, flexible spring steel tooth wire formed into a substantial dental arch, said wire being shaped and arranged to be received in aligned apertures through the anterior-posterior axial line of aligned artificial teeth for the support thereof, lingual and buccal-labial wires of similar dental arch disposed in superposed relation on each side of said tooth wire, said lingual and cubbo-labial wires being joined at their distal extensions to the posterior ends of said tooth wire and a flexible base material embedding all of said wires and the base of said artificial teeth.

3. A flexible denture comprising a resilient, flexible spring steel tooth wire formed into a substantial dental arch, said wire receiving artificial teeth having aligned apertures through their anterior-posterior minor axes, said wire having its ends extended and terminating in joints, a plurality of other wires having their ends fixed in said same joints and a flexible rubber-like base material embedding said plurality of wires and said tooth wire, said teeth projecting from said base material for occlusion with the teeth of another denture or with natural teeth.

4. A flexible denture comprising a resilient, flexible spring steel tooth wire formed into a substantial U-shape, artificial teeth having aligned apertures through their anterior-posterior minor axes receiving said tooth wire therethrough, said wire having its ends extended and terminating in joints, and a flexible and resilient base material embedding all the wire and joints and the base of said artificial teeth, said flexible and resilient base material providing the side support and the saddle of the denture and embracing the alveolar process on the sides thereof with a pressure of approximately forty (40) millimeters.
